Primary Examiner — Eric Goodman

(74) Attorney, Agent, or Firm — Banner & Witcoff Ltd.

(57) **CLAIM**

The ornamental design for a display screen with user interface, as shown and described.

DESCRIPTION

The FIGURE is a front view of a display screen with user interface showing the new design.

The broken line showing of the remainder of the user interface and of the display screen is for environmental purposes only and forms no part of the claimed design.

1 Claim, 1 Drawing Sheet
